Patented Jan. 19, 1960

187,065

VACUUM CLEANER

Dave Chapman, Chicago, Ill., assignor to Scovill Manufacturing Company, Waterbury, Conn., a corporation of Connecticut

Application August 3, 1959, Serial No. 57,044

Term of patent 14 years

(Cl. D9—2)

FIG. 1.

FIG. 2.

FIG. 3.

FIG. 4.

Fig. 1 is a top plan view of a vacuum cleaner embodying my new design.

Fig. 2 is a side elevational view thereof, the opposite side not shown being substantially the same.

Fig. 3 is a front elevational view thereof; and

Fig. 4 is a rear elevational view thereof.

I claim:

The ornamental design for a vacuum cleaner, as shown and described.
